Arthur N. Van Horne,

His ATTORNEY

UNITED STATES PATENT OFFICE

ROY M. HIGGS, OF CLEVELAND, OHIO

TABLE TOP

Application filed February 11, 1929. Serial No. 338,953.

My invention is an improvement in article supports such as table tops and relates more particularly to table tops formed of a single sheet of material.

5 One of the objects of my invention is to maintain the supporting surface of a table top, or the like, in substantially the same plane throughout its supporting area when in use.

10 Another object of my invention is to form a table top of a single sheet of material and reinforcing the supporting area of the said top against deformation.

Another object of my invention is to construct a rigid, durable and inexpensive reinforced table top of light gauge sheet material.

15 Other objects and advantages of my invention will become more apparent from the following description of an embodiment thereof.

20 reference being made to the accompanying drawing in which like reference characters are employed to designate like parts throughout the same.

In the drawing—

25 Fig. 1 is a bottom perspective view of a table top embodying my invention, and

Fig. 2 is a transverse section taken on line 2—2 of Fig. 1.

In carrying out my invention I provide 30 a table top formed of a single sheet of material and having a peripheral flange 1. The supporting area 2 of the table top lies substantially in the same plane throughout.

I have provided means for reinforcing the 35 supporting area of the table top and for maintaining the same in its normal plane with respect to the flange. Such means includes

a reinforcing rib 3 pressed into the top material by suitable dies. This rib is of closed

40 U-shaped cross section and extends preferably longitudinally inwardly of the table top and intermediate the ends thereof. It will be noted that the side walls of the rib are

45 pressed together into intimate contact and that their abutting upper edges 4 provide a substantially continuous surface with the remainder of the supporting surface.

I apply enamel 5 to the entire surface of 50 the table top including the flanges and rib and bake the same in the usual manner. In

this manner I have provided a strong, rigid and sanitary table top having a continuous, reinforced supporting surface extending throughout its area in substantially the same plane.

55 By my invention, I am enabled to use a sheet of material of much lighter gauge than has been used heretofore in the manufacture of table tops. Before my invention, I have found that it was necessary to use heavy 60 gauge sheet to assist in reinforcing the supporting area. The use of heavy gauge sheet was not only expensive and wasteful, but it did not sufficiently reinforce the supporting area of the table top to prevent sagging under load 65 or buckling when the load was removed. By the use of my invention these disadvantages are eliminated and at the same time the cost of manufacture is materially reduced.

70 Various changes may be made in the details of construction and arrangement of parts without departing from the spirit of my invention or the scope of the subjoined claim.

I claim:

75 An integrally formed reinforced table top including a supporting area having a portion pressed inwardly to form a closed reinforcing rib for the said area, the adjacent walls of the rib being pressed tightly together in 80 contractual relation throughout their extent, to form a smooth supporting surface for the table top, said walls being parallel and extending substantially at right angles to the supporting surface.

85 In testimony whereof, I hereunto affix my signature.

ROY M. HIGGS.
